UNITED STATES PATENT OFFICE.

FRANK ANDERSON, OF PEEKSKILL, NEW YORK.

GOVERNOR.

SPECIFICATION forming part of Letters Patent No. 267,965, dated November 21, 1882.

Application filed September 7, 1882. (No model.)

To all whom it may concern:

Be it known that I, FRANK ANDERSON, of Peekskill, in the county of Westchester and State of New York, have invented a new and useful Improvement in Governors; and I do hereby declare that the following is a full, clear, and exact description of the same.

My invention is an improved governor, the object of the invention being to regulate the speed of the machinery to which it is applied, and at the same time to save the expenditure of power beyond that required to maintain a given rate of speed.

My invention is more especially designed for use in machines impelled by hand or foot power.

The essential principle of the invention is that centrifugal force caused by speed in excess of that required acts upon a pressure piece or pieces and releases the driving-shaft from the driving mechanism, thereby relieving the driving-power of the work while the parts are so disconnected.

Heretofore governors have been commonly used which operate by centrifugal force generated by rapid revolution, creating friction to consume the power in excess of that required; also, governors are commonly used which by centrifugal action shut off the energy or motive power, thereby reducing the speed by reducing the force applied to the machine. In my invention the governor determines the amount of force which it will receive from the motive power by letting go the grasp upon the communicating mechanism when a speed is attained beyond the determined limit.

In the accompanying drawings I have shown the best means known to me for carrying my invention into effect.

In these drawings, Figure 1 shows a side elevation of a shaft with my improved governor and the driving-pulley attached. Fig. 2 shows a front elevation of the governor. Fig. 3 shows a central transverse section of the governor and pulley; Fig. 4 a section on line $\alpha\alpha$, and Fig. 5 a detail.

In this form of the invention the governor is combined with a fly-wheel and driving-pulley. This fly-wheel is shown at M, and is rigidly attached to the shaft K, which communicates motion to the machine. The rim is made

proportionately heavy, and is preferably square or nearly square in cross-section, with the web which connects the rim to the hub located as far to one side as possible, as shown in Fig. 3. 55 Adjacent to the fly-wheel, but loose on the shaft K, is a pulley, L, which has a horizontal rim, l, extending on one side beyond the hub of the pulley. The pulley may be of any form convenient for the transmission of power, and it is to be connected by band or equivalent device to a treadle or wheel to be operated by any power, as of the foot or hand of the operator, as in telegraphic perforators, sewing-machines, and the like, or by animal-power, 60 as in grain-separators and like machines. The rim l extends into the cavity of the fly-wheel, and is of slightly less diameter than the inside of fly-wheel rim. Sections m m of the rim of the fly-wheel are cut out of the latter 70 and are held in their position by the springs m' m' on the outside of the wheel. These springs admit of a slight outward movement of segments m m. On the inner side of the segments pieces of leather l' or other proper 75 material are placed, which project sufficiently to touch with some pressure the periphery of the rim l of the pulley, the pressure being insured by the action of the springs m' m'. It will be seen that if the pulley is revolved the 80 friction between the rim of the pulley and the leather on segments m can be made sufficient to cause the fly-wheel to revolve also; and it is also evident that as the speed increases the centrifugal action of the segments or weights 85 will also increase till it equals or overcomes the resistance of the springs, and the friction between the two surfaces will cease. Consequently the speed cannot be increased beyond a point where the centrifugal action relieves 90 the friction, no matter how fast the pulley may revolve. The springs m' m' are made not quite strong enough to insure full speed, and are then re-enforced by the spiral springs m'' m'', the strain of which is easily regulated by 95 set-screws which pass through thin slotted pieces into the segments, thereby clamping these pieces adjustably to the segment at l' l'', thus affording a ready means of adjusting the speed. I have shown two of the segments or pressure-pieces, but obviously the number is not material. Nor is it essential that the seg-

ments should be attached to a fly-wheel. Any intermediate wheel or support fixed to the shaft and holding the segments which bear against the rim of the pulley will serve the same purpose.

By the apparatus above described it will be obvious that an increase of speed above a certain determined limit disconnects the driving-power from the mechanism to be driven, and thus at the same time reduces the speed and keeps it within a certain limit and relieves the driving-power of the work when the speed is in excess of the prescribed limit.

Having thus described my invention, what I claim is—

1. An improved governor, consisting of a pressure piece or pieces, connected by intermediate support to the shaft of the machine, a pulley or like device for communicating motion, loose upon said shaft, adapted to receive the pressure of the pressure-pieces, and suitable springs to cause the pressure-pieces to bear

upon the pulley, the parts being constructed and operating in relation to each other as described, whereby increase of speed beyond a certain limit releases the pulley from connection with the shaft, substantially as set forth.

2. The combination, with the main shaft, of a fly-wheel fixed to shaft, pressure-pieces connecting therewith, and a pulley loose on said shaft, the said pressure-pieces being adapted to connect the shaft to the pulley and to be released therefrom by centrifugal force, as set forth.

3. The combination of the fly-wheel M, shaft K, pulley L, flange l, segments m, and their springs, substantially as described.

In testimony whereof I have signed my name to this specification in the presence of two subscribing witnesses.

FRANK ANDERSON.
